UNITED STATES PATENT OFFICE.

JOHN DUNCAN, OF BOONE, IOWA.

CAR END CONSTRUCTION.

1,350,442.

Specification of Letters Patent. Patented Aug. 24, 1920.

Application filed October 23, 1919. Serial No. 332,615.

To all whom it may concern:

Be it known that I, JOHN DUNCAN, a citizen of the United States, residing at Boone, in the county of Boone and State of Iowa, have invented certain new and useful Improvements in Car End Construction, of which the following is a specification.

This invention relates to car end constructions, and more particularly to means for retaining the end posts in position.

The car end post retaining means in use today takes the form of pockets which are doweled into the wooden end sills. Under pressure, these pockets are tipped over and the end posts are forced out of operative association therewith, thereby greatly weakening the car end structure. Also these pockets when subjected to pressure break away the upper and outer portions of the end sill. Although the wood of such end sill is perfectly strong, it is practically impossible to use such end sills when so damaged, especially with the pockets in question.

Accordingly, the object of this invention is to provide simple and novel means whereby the end posts may be retained in place, such means being applicable to damaged end sills for repair work as well as in new constructions.

This and other objects are accomplished by means of the arrangement disclosed on the accompanying sheets of drawings, in which—

Figure 1 is an end view of a railway car embodying my invention;

Fig. 2 is a fragmentary sectional view of the same car taken in the plane of line 2—2 of Fig. 1;

Fig. 3 is a detail sectional view of the end portion of the car showing, among other things, my improved means for securing end posts to the top plate and end sill;

Fig. 4 is a fragmentary top plan view of a modified form of bracket which operatively connects the end sill and a frame portion of the car;

Fig. 5 is a sectional view taken in the plane of line 5—5 of Fig. 4; and

Fig. 6 is a fragmentary detail rear elevation of the bracket connected to an end post and end sill, as shown in Figs. 4 and 5.

The various novel features of my invention will be apparent from the following description and drawings, and will be particularly pointed out in the appended claims.

Referring to the figures of the drawings, it will be noted that I have illustrated my invention in connection with a freight car, including sides 10 and ends which, among other things, include an end sill 11, end plate 12, and end posts 13.

As mentioned hereinabove, heretofore the retaining means for end posts have taken the form of pockets which have been doweled into the end sills, the pockets being tipped over under pressure, causing the end posts to be forced out of operative association with the pockets and end sills, thereby weakening the end structure of the car and many times breaking away the upper and outer corner of the end sill, making further use of the latter impossible.

In my present construction, I have shown the end posts 13 in the form of I-beams having flanges 14. I choose to operatively connect the end sills with the end posts by means of brackets 15 having a main web 16 and oppositely extending flanges 17 and 18, the bracket therefor being of Z-shape. The web of the bracket 15 rests upon the upper surface of the end sill 11 and is interposed between the latter and the lower end of the end post 13, the outer flange 17 being secured to the outer flanges 14 of the end post 13 by rivets or bolts 19. The inner flanges 18 hook over or embrace the inner sides of the end sill 11, the bracket 15 preferably being secured to the end sill by bolts 20, which pass through the end sill 11 and the web 16 of the bracket at a point preferably behind the end post. By thus operatively securing the end post to the end sill, there is no possibility for the end sill to become damaged.

Furthermore, if it is desired to apply my bracket arrangement to a damaged end sill for repair work, the same may be easily accomplished in the manner hereinabove described. The upper end of the end posts in each case is secured to the end plate 12 by a similar Z-shaped bracket 21, the inner flange of the bracket being hooked over or embracing the inner side of the end plate 12 and secured thereto by a bolt 22, the outer flange of the bracket 21 being secured to the outer flanges of the end posts by rivets or bolts 23. It will be appreciated that the end posts may be of wood and be of forms other than an I-beam, whether of wood or metal.

Referring particularly to Figs. 4, 5, and

6, it will be noted that I have shown a composite bracket for operatively connecting the end posts 24 with an end member of the car such as an end sill 25, one member of the 5 composite bracket being in the form of an angle 26, the vertical flange 27 of which is secured to the end post 24 by any suitable means, such as by rivets 28, the horizontal portion 29 of the bracket member 26 being 10 provided with a toothed portion 30 which meshes and coöperates with a toothed portion 31 on the horizontal leg 32 of the other bracket member 33, which has a depending vertical flange 34 which embraces an inner 15 side of the end sill 25.

The horizontal leg 32 of the bracket 33 is provided with an elongated opening 35 for the reception of the fastening bolt 36. The horizontal portion 29 of the upper bracket 20 member 26 is provided with a plurality of openings 37, whereby the bracket members 26 and 33 may be selectively secured to each other in various meshing positions. By 25 means of this arrangement, end sills or other end portions of the car having varying dimensions may be operatively secured to the end post in a simple manner.

For further adding to the strength of the

end construction, brace rods 38 are provided, 30 which extend from the car sides to the end posts 13, said reinforcing members extending diagonally across the corners, as particularly shown in Fig. 2 of the drawings.

There may be various modifications of my invention, and it is my intention to cover 35 all such modifications which do not involve a departure from the spirit and scope of the invention as set forth in the following claims.

I claim:

1. In a railway car, an end sill, an end post, and a bracket operatively connecting the same comprising a plurality of relatively adjustable parts whereby said bracket is applicable to end sills and posts which 45 may have different dimensions.

2. In a railway car, an end sill, an end post, and means for operatively connecting said end sill and end post, said means comprising relatively adjustable tooth-members 50 whereby end sills and end posts of various dimensions may be operatively connected by such means.

Signed at Boone, Iowa, this 9th day of October, 1919.

JOHN DUNCAN
